Primary Examiner — Darcey E Gottschalk(74) *Attorney, Agent, or Firm* — The Law Office of Scot S. Fagerland, PC(57) **CLAIM**

The ornamental design for a jar candle cap, as shown and described.

DESCRIPTION

FIG. 1 is an upper perspective view of a jar candle cap.

FIG. 2 is a lower perspective view.

FIG. 3 is a front elevation view.

FIG. 4 is a rear elevation view.

FIG. 5 is a top plan view.

FIG. 6 is a bottom plan view.

FIG. 7 is a right elevation view; a left elevation view is not explicitly shown but is a left-right mirror image of FIG. 7; and,

FIG. 8 is a rear cross-sectional elevation view, taken along the line 8-8 from FIG. 5.

The broken line arrows represent a sectional designation that forms no part of the claim.

1 Claim, 6 Drawing Sheets(56)
